(57) **CLAIM**

We claim the ornamental design for a lure, as shown and described.

DESCRIPTION

FIG. 1 is a perspective view of a first embodiment of a lure; FIG. 2 is a cross-section view taken across line 2 of the first embodiment of the lure as illustrated in FIG. 5 to show depth of apertures that make up the first embodiment of the lure; FIG. 3 is a right side elevation view of the first embodiment of the lure, the left side elevation view being an identical view thereof;

FIG. 4 is a bottom plan view of the first embodiment of the lure;

FIG. 5 is a top plan view of the first embodiment of the lure; FIG. 6 is a rear elevation view of the first embodiment of the lure;

FIG. 7 is a front elevation left side elevation view of the first embodiment of the lure;

FIG. 8 is a perspective view of a second embodiment of a lure;

FIG. 9 is a right side elevation view of the second embodiment of the lure, the left side elevation view being an identical view thereof;

FIG. 10 is a bottom plan view of the second embodiment of the lure;

FIG. 11 is a top plan view of the second embodiment of the lure;

FIG. 12 is a rear elevation view of the second embodiment of the lure; and,

FIG. 13 is a front elevation left side elevation view of the second embodiment of the lure.

The broken lines depict portions of the lure that form no part of the claimed design.

1 Claim, 6 Drawing Sheets
